UNITED STATES PATENT OFFICE

EUGENE ROBERTS, OF HASTINGS, NEW YORK, ASSIGNOR TO THE WESTERN STATES MACHINE COMPANY, OF SALT LAKE CITY, UTAH, A CORPORATION OF UTAH

APPARATUS FOR DISCHARGING CENTRIFUGAL MACHINES

Application filed April 15, 1931. Serial No. 530,224.

This invention relates to the discharging of centrifugal machines of the sugar centrifugal type characterized by foraminous basket secured to a central gyratory shaft and having a bottom discharge opening through which the walled up solid material may be discharged to permit reloading the basket with a new charge to be centrifugally treated.

10 One object of the present invention is to provide means for automatically controlling the discharging operation without requiring the attendance of the operator, so that as soon as the charge of material in the basket 15 has been properly centrifuged the solid residue walled up on the interior of the basket may be discharged through the bottom of the basket without danger of breaking or injuring the apparatus, so that the machine 20 may be emptied to receive the next load whether the next load is automatically charged into the machine or charged by hand control.

With such objects in view the invention 25 embraces, generally speaking, a discharging apparatus comprising a carrier head mounted inside the basket and provided with plows or disrupting means for breaking down and discharging the walled up material through the bottom of the basket, combined with suitable retarding and lifting mechanism by which the discharging plows 30 may be actuated through association with controlling and actuating mechanism that 35 is coordinated with the centrifugal driving and braking mechanism, whereby upon the cutting off of the drive and the setting of the brake, the discharging apparatus automatically acts, through its association with 40 such driving and braking mechanism, to discharge the material through the bottom of the centrifugal.

These and other features of my invention 45 will be described in the following specification and will be defined in the claims hereto annexed.

In the accompanying drawings I have 50 illustrated a well known type of gyratory centrifugal equipped with one form of automatically controlled discharging apparatus

embodying the principles of my invention.

In said drawings

Fig. 1 is a side elevation, partly in section, illustrating the application of my improvement to such a centrifugal. 55

Fig. 2 is a plan view, partly in section, of the mechanism shown in Fig. 1 on a plane slightly above the level of the centrifugal basket and curb.

Fig. 3 is an enlarged detail view of the 60 overhead valve through which the actuating mechanism for lifting the head is energized to raise the head when starting the machine in operation.

Fig. 4 is a detail view showing the automatic control mechanism mounted on the main air cylinder as viewed in the plane of the broken line X—X of Fig. 1. 65

Fig. 5 is a detail view showing in elevation, as viewed in the plane Y—Y of Fig. 4, 70 the ratchet controlled means by which the main valve lever is actuated on alternate upward strokes of the piston rod of the main chamber.

Fig. 6 is a detail view showing in cross section, on plane Z—Z of Fig. 4, the ratchet and valve mechanism carried on the head of the main piston. 75

Fig. 7 is a detailed view on the plane W—W of Fig. 4 showing the automatically 80 shifting, lifting and valve control mechanism.

The discharging mechanism is here shown as applied to a well known type of centrifugal machine embracing the usual gyratory 85 central driving shaft 1, to whose lower end the basket 2 is firmly secured by means of a radial spider 4 fastened in the central discharge opening in the bottom 3 of the basket. The basket has the usual top ring 5 surrounded with the usual stationary curb or casing 6, which collects the centrifugally 90 expelled liquid. The center of gyration, or suspension, in this case is at *a* in the usual socketed hanger A and there is provided a well known type of starting lever *c* which occupies the rearward position (toward the right in Fig. 1) when the machine is at rest and the brake is set, but which can be moved 95 forward by hand or otherwise successively 100

to the low speed and the high speed driving positions, in both of which positions of course the brake is released. The above recited construction is well known in the art and is illustrated in my Patents No. 1,719,132 and No. 1,758,901, the brake and driving mechanism being omitted as forming no part of the present invention and as well understood in the art.

10 On the central driving shaft 1 is slidably mounted a carrier head 10 provided at its upper end with an annular grooved clutch spool 10^a, and carrying on its bottom lateral extension 10^b a pair of hollow bosses 12^a, in which is pivotally mounted at 11^a laterally projecting plows 11 which can swing outward close to, but not to exert pressure against, the perforated lining or screening on the inside of the basket wall. Since this carrier head is supported by the rotary shaft and the rotary basket, it normally partakes of its rotary movement, although being free to rotate in relation to the basket and shaft if retarded by any appropriate retarding means. The lateral extension 10^b, which serves as a support for the discharger plows, may also serve when given a circular form to act as a closure for the discharge opening occupying the central part of the basket bottom 3. The clutch spool 10^a at the top of this head is adapted to be engaged by a pair of opposed clutch blocks 12, which are pivotally mounted in supporting and actuating arms 13 that are fulcrumed about a common pivot 14 in the lifting head 15, which projects from the inner end of the lifting lever 16. This lifting lever 16 is pivotally mounted at 17^a in a pair of links 18 which are fulcrumed at 19 on top of the curb. The lever also has an outward extension 16^a which acts as a power arm for lifting the head by its actuating means, which in this case comprises a compressed air cylinder 31 pivotally mounted on a fixed bracket 30 and containing a slide piston 32 to which is secured the piston rod 33 having a pivotal engagement with the outer end of the power arm 16^a of the lifting lever. There is a smaller compressed air cylinder 20 containing a piston 20^a, to the inner end of whose piston rod 20^b is pivotally attached a pair of toggle levers or links 17 which are pivotally connected with the outer ends of the clutch levers 13, so that when the piston 20^a is forced inward under the pressure of air the toggle links are expanded to force the clutch blocks or shoes 12 into firm engagement with the clutch spool formed at the head of the vertically slidable carrier head 10. A return spring 21 yields under the air pressure to allow the piston 20^a to move inwardly to grip the clutch shoes against the carrier head, while acting to return the piston when the air pressure behind it is relieved.

It will be understood that pressing the clutch blocks 12 into braking engagement with the spool end of the carrier head acts to produce a frictional retardation of the head and of the plow or plows carried by it, so that the more slowly revolving plows dig out and discharge the walled up material which is revolving faster than are the plows. Where a flat bottom basket is used, as illustrated in the present drawings, with a bottom closure or valve the latter must be lifted from the bottom of the basket to a more or less open position to allow the sugar to pass through the bottom opening. Consequently, it is preferable in such case to lift the carrier head 10 before effecting such serious retardation of the head, the plow being provided with a lost motion connection, as shown in Fig. 1, permitting the bottom valve to lift a short distance before the plow raises. Thereafter, the lifting and retardation of the plow serves to shear away the walled up material and discharge it through the bottom discharge opening. After the carrier head and plows are lifted to the topmost position, the compressed air supply is cut off and the valve and lifting head allowed to drop to low position to close the bottom discharge opening, the compressed air confined behind the pistons being vented by serving as a cushion for preventing shock when the bottom discharge valve and the head are dropped. In my pending application, Serial No. 516,372, the above described mechanism was disclosed and explained in detail, but in that case the control of the mechanism was through manual manipulation, which required the attendance of the operator.

In the present case the different mechanism for retarding the carrier head to produce a differential rotation and the lifting and the return of the carrier head is effected by a control mechanism that is governed by the starting and braking of the centrifugal and this self-acting control will now be described in detail, it being understood that the present application of power for actuating these movements is through the medium of compressed air, although I do not limit myself to such an actuating medium in the practice of this invention.

The compressed air supply for present purposes is furnished through the supply pipe 37^a from which lead two separate branches 40 and 36^a, whose lower ends are connected by flexible hose connections 40^a and 36 with the actuating mechanism in the manner now to be described.

At approximately the suspension level of the centrifugal, the air pipe 40 is provided with a valve 41, which is of the rocker type provided with an actuating arm 42 which occupies the rearmost position of its move-

ment when the valve is closed and which moves to the forward position to open the valve to admit compressed air into the cylinder 31 above the piston 32.

As it is preferred to open the valve when moving the starting and brake-releasing lever *c* to first or low speed position, while still permitting said lever thereafter to be moved forward to high speed position, I provide an over-the-center throw by pivotally connecting with the valve arm 42 a pivoted link 43 having a compression or thrust spring 44, which has a double action, namely, as soon as the pivotal center has passed to one side of the straight line position the spring quickly throws the valve to its extreme position on that side and the same action takes place when it is moving in the opposite direction. The pivot pin connecting the toggle couple 42 and 43 extends through a slot 45 in the link 46, which is pivotally attached to the centrifugal control arm *c*. With the toggle couple in the rearmost or right hand position, as shown in Fig. 1, and with the control lever *c* in its rearward non-starting and brake-setting position, the connecting pin occupies the rear part of the slot 45, but when the lever *c* is thrown forward to second speed position, also releasing the brake, the movement of the link 46 is sufficient to pull the actuating pin of the toggle beyond the dead center line, thus allowing the thrust spring 44 to force the toggle to the left hand or forward position. As the link 46 has moved forward, this movement leaves sufficient length of the slot behind the pin in its forward position to allow movement of the starting lever from low speed to high speed position.

When the control lever of the centrifugal moves back to rearward position at the time of cutting off the power and setting the brake, the forward end wall of the slot 45, pushes the toggle couple rearwardly beyond the dead center allowing the toggles to return to the position shown in Fig. 1, thereby closing the valve and opening the vent.

It should be understood that the air duct 40 leading into the upper end of the cylinder supplies air only for the purpose of raising the lifting head (when disengaged from the clutch spool) out of the basket to idle position in order to get it out of the way when loading and operating the centrifugal, the carrier head being left in bottom closing position. In Fig. 3 is shown in dotted lines the position of the valve arm 42 when the centrifugal is in normal operation, during which time the compressed air supply through pipe 41 keeps the piston 32 at the bottom of its cylinder.

However, when the control lever *c* is moved rearwardly into position to cut off the power and apply the brake, the valve

arm is moved to full line position in Fig. 3, thereby cutting off the air supply and opening communication with the vent passage 41^b, whose capacity can be regulated by the needle valve 41^a to allow the lifting head to drop gently to its lowermost position where the clutch blocks are on a level with the spool 10^a. When the lifting head drops into the basket its outer extension 16^a, connected to the piston rod, raises until a projecting prong or finger 33^a carried by the arm 16^a engages a registering finger of the star wheel 38^a thereby lifting the star wheel and the sleeve 38 mounted on the valve opening slide rod 37. The lower end of this valve rod 37 is pivotally connected with an arm 35 secured to the rock valve 34 and the lifting of this arm 35 opens communication through the valve between the air supply tube 36 and an outlet tube 22, which leads to the head of the cylinder 20. Therefore, by the lifting of the valve arm 35 air is admitted first through tube 22 behind the piston 20^a to the cylinder 20, thus forcing that piston inwardly and thereby engaging the clutch blocks 12 with the retarding spool 10^a. As soon as the piston 20^a has moved inwardly far enough to engage the clutch blocks with said spool, it uncovers a lateral port in the cylinder 20, which is connected with an inlet opening in the head of the cylinder 31 to allow part of the compressed air to escape into cylinder 31 above the piston 32, thus forcing down the piston 32, which is the lifting piston, while at the same time continuing to exert braking or retarding pressure through the clutch blocks upon the spool 10^a. These two pistons continue to function until the upwardly moving plows have reached their topmost position with the carrier head 10 inasmuch as the very small vent in the valve 41 has no appreciable effect in proportion to the volume of compressed air supply to the respective cylinders through the valve 34 and the conduits 22 and 23.

To prevent the prong 33^a from engaging a tooth of the star wheel 38^a on the next downward traverse of the head, provision has been made for partial rotation of the star wheel 38^a to bring one of the intermediate spaces or notches into registry with the lifting member 33^a so that the lifting member 33^a passes up between two fingers of the star wheel without lifting it and therefore without opening the valve 34.

It is therefore apparent that the opening of the valve 34 is effected only on each alternate upward stroke. The first upward stroke is effected when the idling head drops into its lowermost position following the return of the centrifugal control lever *c* to power-idling, brake-setting position and acts as above explained to open valve 34 to apply power to the plow actuating or the

discharger mechanism. The second upward stroke of the piston 32 merely allows the carrier head and the lifting head to drop downward after they have performed their work.

Any suitable form of mechanism may be employed to secure this alternating opening of the valve 34 on the upward stroke. In the present case I have employed a rotatable tubular sleeve 38, mounted on the slide rod 37, which is pivotally connected with the valve arm 35, to have rotation thereon, but anchored between top and bottom collars to prevent sliding movement of the sleeve 5 on said valve actuating rod. At the upper end of this sleeve is secured the star wheel 38^a with ample spaces between the peripheral teeth or prongs. At the lower end of this sleeve is secured a ratchet wheel 38^b having twice as many teeth as the star wheel 38^a and beneath the sleeve pivoted on the valve rod 37 is a ratchet arm 38^c carrying a pawl 38^d at its rear end and provided with a cam-like surface at its forward end adapted to engage a downwardly projecting blade 33^b, whose lower end is tapered as shown in Fig. 5 to engage and rotate the ratchet arm 38^c through the arc of one tooth of the ratchet wheel 38^b in a clockwise direction. The ratchet arm 38^c is returned to initial position, when freed of the cam member 33^b, by means of a spring 38^e, as shown in Fig. 6.

It will therefore be seen that each time the arm 16^a moves downward the attached cam member 33^b which it carries engages and moves the ratchet one tooth. One such movement moves a tooth of the star wheel into alignment with the lifting prong 33^a, while on the next downward movement the ratchet moves the sleeve and star wheel to bring a notch in the star wheel in registry with the lifting prong and this alternating action is repeated indefinitely.

Since the valve 34 is open when its arm 35 is in raised position, it will be closed by the depression of said arm by means of a pin 33^e projecting from the upper end of the piston rod when the piston descends to its low position.

Preferably in the case of a flat bottom basket such as shown in the drawings, the head should drop before the centrifugal comes to a stop in order to allow the discharger to receive any sugar that may have fallen upon the bottom, but in the case of a self-discharging basket with a steeply inclined frusto-conical bottom this might not be the case. The speed of dropping may be controlled through adjustment of the air vent.

What I claim is:

1. The combination with a gyratory centrifugal, including driving and braking means, whose basket is provided with a central discharge opening in the bottom, of a

discharging apparatus embracing a plow-carrying head slidably mounted on the centrifugal shaft, and a discharging plow arranged thereon to cut down the walled up material in the basket, means for frictionally clutching and retarding said head after rotation of the centrifugal has been retarded by application of its brake, means for lifting said head actuating means for operating said clutching and said lifting means when the drive control of the centrifugal has been cut off and the brake is applied to cause the plow to discharge the solid walled up material through the bottom of the basket.

2. The combination with a gyratory centrifugal, including driving and braking means, whose basket is provided with a central discharge opening in its bottom, of a discharging apparatus embracing a plow and its support mounted loosely on the basket shaft inside the basket to revolve on the shaft, means actuated after the setting of the centrifugal brake for retarding the revolution of the plow to cause it to lag behind the retarded centrifugal and for lifting it toward the top of the basket, and means coordinated with the centrifugal driving and braking mechanism for energizing said retarding and lifting mechanism to cause the plow to shear away the walled up material inside the basket to discharge it through the bottom of the basket.

3. The combination with a gyratory centrifugal, including driving and braking means, whose basket is provided with a central discharge opening in its bottom, of a discharging plow mounted inside the basket to permit it to revolve with the basket, a support therefor loosely mounted on the basket shaft, means for frictionally engaging said support to retard its revolution in relation to the basket, said retarding means being controlled through the agency of the brake setting mechanism of the centrifugal after the brake has been applied to retard the centrifugal to actuate the plow retarding means and thereby cause discharge of the solid material in the basket through the bottom opening therein.

4. The combination with a gyratory centrifugal, of a discharger plow, a supporting head therefor loosely mounted on the shaft of the centrifugal, a retarding clutch movable into braking engagement with said support to cause the support and plow to revolve at slower speed than the basket, an air actuated piston for gripping said clutch upon said supporting member, and an air controlled valve energized through the action of the brake setting mechanism to admit air to the piston to cause said clutch to operate when the brake is applied to the centrifugal.

5. The combination with a centrifugal whose basket is provided with a central opening in its bottom, of discharging ap-

paratus embracing a discharger plow, a supporting head therefor loosely mounted on the centrifugal shaft to permit independent sliding and rotating movements in relation thereto and normally revoluble with the basket, means adapted to frictionally engage and retard said plow support, means for lifting said plow support, separate coordinated power actuated members for actuating, respectively, said retarding means and said lifting means, said actuating members being controlled through the centrifugal starting and braking mechanism.

6. The combination with a centrifugal, including driving and braking means, whose basket is provided with a central opening in its bottom, of discharging apparatus embracing a discharger plow, a supporting head therefor loosely mounted on the centrifugal shaft to permit independent sliding and rotating movements in relation thereto, said head being constructed to act as a closure for the bottom opening, means adapted to frictionally engage and retard said plow support, means for lifting said plow support, separate coordinated power actuated members for actuating, respectively, said retarding means and said lifting means, said actuating members being energized by the setting of the centrifugal braking mechanism.

7. The combination with a centrifugal whose basket is provided with a central bottom discharge opening, of discharging apparatus embracing a plow supported head and a plow mounted inside the basket to normally revolve therewith, means for retarding the revolution of the head and plow relative to the revolving basket, said means including an air actuated piston and valve mechanism by which the action of the piston is controlled, said valve mechanism being associated with mechanism controlling the starting and stopping of the centrifugal to render said retarding means active and inactive at predetermined stages in the operation of the centrifugal.

8. The combination with a centrifugal whose basket is provided with a central bottom discharge opening, of discharging apparatus comprising a discharger device mounted inside the basket and normally revoluble therewith, separate means for retarding the revolution of the discharger and for raising it from the bottom of the basket, an actuating piston for effecting retardation of the discharger, a second piston for causing the lifting of the discharger, an air control valve operated through the medium of mechanism that controls the driving and braking of the centrifugal to admit compressed air to each of said pistons in a predetermined time-relationship and thereby cause the discharger to discharge the material.

9. The combination with a centrifugal

whose basket is provided with a central bottom discharge opening, of discharging apparatus embracing a discharger head and plow mounted in the basket, separate air actuated pistons for operating said discharger and plow to discharge material through the basket bottom, coordinated valve mechanism co-operatively associated with mechanism that controls the starting and stopping of the centrifugal and acting to admit compressed air to said pistons for operating the discharger and to permit the return of the discharger to inactive position at predetermined stages in the operation of the centrifugal.

10. The combination with a centrifugal whose basket is provided with a central bottom discharge opening, of discharging apparatus embracing a revoluble discharger head and plow mounted inside the basket, actuating means comprising separate pistons for operating said plow and causing it to traverse the basket vertically, self-acting valve mechanism for admitting compressed air to said pistons and cutting it off therefrom, said valve mechanism being rendered active by the setting of the centrifugal brake.

11. A discharger apparatus for sugar centrifugals embracing, a plow supporting head and a plow adapted to be revolvably mounted in the centrifugal basket, a lifting lever pivotally mounted outside the basket and having friction shoes for engaging and retarding a head and for raising and lowering the head, a retarding shoe actuating piston, a separate piston for actuating the lever, coordinated valve mechanism for controlling the supply of compressed air to said pistons to cause operation of the discharger, said valve mechanism being arranged to be energized through mechanism controlled by the braking mechanism of the centrifugal.

12. A discharger mechanism for a sugar centrifugal embracing, a revoluble vertically movable discharger mounted in the centrifugal basket, means for retarding and lifting the discharger, air actuated pistons for causing, respectively, the retardation and the lifting of the discharger valve, mechanism for controlling a supply of compressed air to the respective pistons, including two valves operating in predetermined sequence, one of them acting to energize the pistons for retarding and for lifting the discharger upon the setting of the brake for the centrifugal, the other valve controlling the raising and lowering of the lifting lever without lifting the discharger, said valves operating in alternation.

13. A discharger mechanism for a sugar centrifugal embracing, a revoluble vertically movable discharger device mounted in the centrifugal basket, means for retarding and for lifting the discharger, air actuated pis-

- tons for causing, respectively, the retardation and the lifting of the discharger, valve mechanism for controlling the admission of compressed air to the respective pistons comprising two alternately operating valves, one of which is controlled by means of the centrifugal control mechanism, the other being controlled by the movements of the lifting piston itself.
- 10 14. A discharger mechanism for sugar centrifugals embracing, a revoluble vertically movable discharger mounted in the centrifugal basket, means for retarding and for lifting the discharger, air actuated pistons
- 15 for causing, respectively, the retardation and the lifting of the discharger, valve mechanism controlling the supply of compressed air to the respective pistons comprising two alternately acting valves each causing alternate strokes of the lifting piston, one of said valves being controlled by the centrifugal control mechanism, the other being controlled by the up and down movement of the piston on each alternate stroke
- 20 thereof.
- 25

In witness whereof, I have subscribed the above specification.

EUGENE ROBERTS.
